UNITED STATES PATENT OFFICE

OSCAR F. LACKEY, OF BALTIMORE, MARYLAND.

CONCRETE SCOW.

933,314.

Specification of Letters Patent. Patented Sept. 7, 1909.

Application filed April 23, 1909. Serial No. 491,757.

To all whom it may concern:

Be it known that I, OSCAR F. LACKEY, a citizen of the United States, residing at Baltimore city, State of Maryland, have invented certain new and useful Improvements in Concrete Scows, of which the following is a specification.

My invention relates to an improvement in scows, barges and the like, and has for its object to provide a scow or barge of reinforced concrete construction capable of use for all purposes as that of the ordinary scow or barge built of wood or other material.

It has for a further object to provide a scow or barge constructed in accordance with my invention which is rendered less impervious to leakage, possesses equal or greater strength, and is more durable and lasting, as compared with the ordinary scow or barge constructed of wood or other material now in universal use.

With the foregoing objects in view, my invention consists in certain novel features of construction and combinations of parts, which will be hereinafter described and pointed out in the claims.

In the accompanying drawings, forming a part of this specification, in which like numerals are used to designate similar parts as shown in the several views, Figure 1 is a side elevation of a scow constructed in accordance with my invention; Fig. 2 is a plan view of the same; Fig. 3 is a transverse sectional view of a part of the scow, parts being broken away, thus enabling the showing on a larger scale; Fig. 4 is a plan view partially in section and parts broken away as in Fig. 3; Fig. 5 is a sectional view of the corner iron; Fig. 6 is a fragmentary view in side elevation of a part of the frame of the scow; Fig. 7 is a plan view of the parts shown in Fig. 6, the same being partly in section taken on the line 7—7; Fig. 8 is a detail sectional view taken on the line 8—8 of Fig. 7; Fig. 9 is a detail sectional view taken on the line 9—9 of Fig. 7; Fig. 10 is a transverse sectional view of a portion of a scow of a modified form; Fig. 11 is a longitudinal sectional elevation of the structure shown in Fig. 10, and Fig. 12 is an elevation of a modified form of towing bit post.

Referring to the drawings, A indicates generally a scow forming the subject matter of the present invention, from the deck 1 of which rises sides 2 for the support of material to be loaded thereon, said sides con-

sisting of reinforced concrete posts 3 placed at spaced intervals and connected by a web 4 of the same material. At either end of the deck are constructed posts 5 for towing purposes, said posts being formed integral with the deck as are likewise the sides 2.

A fender 6 of wood is secured in a groove 7 formed along the sides 8 of the scow by means of lag screws 9. Between the inner 65 wall of the groove 7 and the fender 6 is placed a layer of packing as indicated at 10, to prevent the ingress of water around the lag screws 9.

Located on the deck at some convenient 70 point, is a man-hole 11, thus permitting access to the interior of the scow, for the purpose of inspection or repair. The sides of said man-hole are formed integral with the deck, and are provided with a cover 12 75 which is ribbed on its under side as indicated at 13, serving the double purpose of strengthening said cover and preventing displacement of same.

The interior of the scow is divided into 80 compartments 14 by concrete bulkheads 15 and in the form shown in Figs. 1 to 4, inclusive, said bulkheads are arranged transversely, while extending longitudinally of the scow, both on the under side of the deck 85 and above the bottom of the scow are ribs 16, and at the juncture of said ribs with the bulkheads 15, are formed posts 17. Man-holes 18 are formed through each of the bulkheads 15, permitting of access to the 90 several compartments 14, and each man-hole is provided with a cover 19.

In Figs. 6 to 9 inclusive, is shown the bare iron or steel frame which consists of side L or angle irons 19. L irons 20 are placed in 95 the posts at the juncture of the bulkheads and the sides, and also in the posts 17, the upper and lower ends of said irons being secured to transversely extending L irons 21. A pair of L irons 22 are placed in the ribs 16 extending longitudinally of the scow, and are upturned at their ends at 23. Plates 24 are secured to the side plates 19 at the bend 23, and plates 25 secure the free ends of the upper and lower bars 19 at their juncture at 105 the prows, and an angle iron 26 caps the said prows, and extends transversely across the structure.

In Fig. 5 is shown a cross section of the irons used in supporting the exposed corners of the structure, and consists of a curved portion 27, having anchoring wings

28 extending therefrom, the same being embedded in the concrete at the corners of the scow, thus preventing chipping thereof.

In Figs. 10 and 11 are shown a structure 5 in which the bulkheads 15 extend longitudinally instead of transversely, as in the previously described structure. Reinforced concrete beams 29 depend from and rise above the deck and bottom respectively. 10 The deck is supported at the man-hole 11 by reinforced concrete posts 30. In other respects the structure is practically the same as that shown in Figs. 3 and 4.

Fig. 12 illustrates a detachable bit post, 15 which is provided with a countersunk headed bolt 31 for attaching to the deck, a metal plate 32 is placed between the post and deck and a reinforced towing bit 33 projects from either side of said post.

20 Slight changes and alterations might be resorted to in the form and arrangement of the several parts described, without departing from the spirit and scope of my invention, hence I do not wish to limit myself to 25 the exact construction as herein set forth; but,

Having fully described my invention, what I claim as new and desire to secure by Letters Patent, is:

30 1. A boat of the character described, comprising a concrete hull, a metal frame reinforcing the said hull, a fender rail exteriorly secured on the sides of the hull, a packing interposed between the fender rail and the said hull, a concrete deck, provided on the said hull and formed integral therewith, and means reinforcing the said deck, substantially as described.

2. A boat of the character described, comprising a concrete hull, a metal frame reinforcing the said hull, a fender rail secured in the side walls of the hull, a packing interposed between the fender rail and said hull, a deck supported by the said frame and integral with the said hull, towing posts mounted upon the said deck and integral therewith, substantially as described.

3. A boat of the character described, comprising a concrete hull, a metal frame reinforcing the said hull, a groove formed in the side walls of the said hull having a

fender secured therein, a packing secured between the said fender and hull, a deck provided on the said hull and formed integral therewith, towing posts mounted on and integral with the said deck, man-holes provided in the said deck and covers securing the said man-holes closed, substantially as described.

4. A boat of the character described, comprising a concrete hull, a metal frame reinforcing the said hull, a plurality of concrete bulkheads provided within the hull, a plurality of compartments formed thereby, a deck formed integral with the said hull, a plurality of ribs extended longitudinal of the said hull and deck, a plurality of posts formed at the juncture of the said bulkheads and ribs forming supports for the said deck, substantially as described.

5. A boat of the character described, comprising a reinforced concrete hull, having a plurality of bulkheads forming compartments within the said hull, man-holes provided in the said bulkheads, a fender rail secured around the sides of the said hull, packing means secured between the said rail and hull, a reinforced concrete deck provided on the said hull and integral therewith, means reinforcing and supporting the said deck on the said hull, towing posts mounted on the said deck and formed integral therewith, substantially as described.

6. A boat of the character described, comprising a reinforced concrete hull, a concrete deck integral therewith, bulkheads forming compartments within the said hull, a plurality of ribs extending longitudinal of the said hull, L irons secured within the said ribs, angle irons extended transversely across the said hull, a plurality of vertically extended reinforced concrete posts formed at the juncture of the said bulkheads and ribs forming supports for the said deck, and means reinforcing the said deck, substantially as described.

In testimony whereof I affix my signature in presence of two witnesses.

OSCAR F. LACKEY.
